UNITED STATES PATENT OFFICE.

ADOLPHI HELLENBERG, OF NEW YORK, N. Y.

DESIGN FOR A SCARF.

SPECIFICATION forming part of Design No. 17,608, dated August 9, 1887.

Application filed June 21, 1887. Serial No. 242,051. Term of patent 7 years.

To all whom it may concern:

Be it known that I, ADOLPHI HELLENBERG, of the city, county, and State of New York, have invented a new and original Design for a 5 Scarf, of which the following is a description.

My newly-designed scarf is fully illustrated in the accompanying drawing, to which reference is made.

The leading feature of my design is a triangle across the head-piece or knot of the scarf.

A represents the head-piece or knot of the scarf, which is keystone shaped in general outline, and shows the upper line, a, side converging lines, b b', the latter interrupted at b'.

15 Across the knot or head-piece A appears diagonal line c. Beneath this appears the triangle B.

C D represent the strings of the scarf, which show the side slightly curved, lines d d', and the

intermediate line, d'. The lower line of the triangle B meets the diagonal line c at the center of the upper part of the string C, and forms the point f, as shown clearly in the drawing.

I claim—

1. The design for a scarf herein shown and described, the same consisting of a keystone-shaped head, A, showing a triangle, B, and also a point, f, central to the head A, substantially as described.

2. The design for a scarf herein shown and described, the same consisting of a keystone-shaped head, A, showing the diagonal line c joining a short converging edge, b', below the top a of the head.

ADOLPHI HELLENBERG.
